CLAIM

The ornamental design for a portable power bank with speaker and phone stand, as shown and described.

DESCRIPTION

FIG. 1 is a front, right, and top perspective view of a portable power bank with speaker and phone stand showing my new design;

FIG. 2 is a rear, left, and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged view of portion 9 shown in FIG. 1;

FIG. 10 is an enlarged view of portion 10 shown in FIG. 1;

FIG. 11 is a rear, right, and bottom perspective view thereof, where the phone stand is folded and received at the bottom of portable bank with speaker;

FIG. 12 is an exploded rear, right, and top perspective view thereof, where the charging cord is separated from the portable power bank with speaker; and,

FIG. 13 is a front, right, and top perspective view thereof, where the portable power bank with speaker and phone stand is shown in an environment of use.

The dash-dash broken lines in the drawings depict portions of the portable power bank with speaker and phone stand that form no part of the claimed design. Additional dash-dash broken lines in FIG. 13 showing a mobile phone illustrate environment and form no part of the claimed design. The dot-dash broken lines shown in FIGS. 1, 9, and 10 represent boundaries of enlarged portion and form no part of the claimed design.
